[57] CLAIM

The ornamental design for a “portion of a cover for a portable electronic apparatus”, as shown and described.

DESCRIPTION

FIG. 1 is a rear elevational view of a portion of a cover for a portable electronic apparatus showing my new design; FIG. 2 is a rear, left side and bottom perspective view thereof; and, FIG. 3 is a rear, right side and top perspective view thereof. The dotted lines showing the outline of a portable electronic apparatus is for illustration purposes only and forms no part of the claimed invention.
